UNITED STATES PATENT OFFICE.

LYMAN J. RHOADES, OF FOND DU LAC, WISCONSIN.

ADJUSTABLE AND EXTENSIBLE BRACKET.

No. 877,373.

Specification of Letters Patent.

Patented Jan. 21, 1908.

Application filed September 12, 1907. Serial No. 392,546.

To all whom it may concern:

Be it known that I, LYMAN J. RHOADES, a citizen of the United States, residing at Fond du Lac, in the county of Fond du Lac and State of Wisconsin, have invented certain new and useful Improvements in Adjustable and Extensible Brackets; and I do declare the following to be a full, clear, and exact description of the invention, such as will enable others skilled in the art to which it appertains to make and use the same.

My invention has relation to new and useful improvements in adjustable and extensible brackets, and while it is primarily designed and is especially adapted for use by dentists and physicians as a support for their tools, etc., it may be used in all cases where use of such a bracket would prove desirable and advantageous.

20 The object of my invention is the production of a simple, economical, ornamental and novel bracket that may be extended or adjusted to answer all purposes required of a device of this character.

25 A further object of the invention is to embody in a bracket means whereby it may be securely locked in position after being properly adjusted.

With these objects in view the invention 30 consists of certain novel features of construction, combination and arrangement of parts as will be more fully described and particularly pointed out in the appended claims.

In the accompanying drawings, Figure 1 35 is a view in side elevation of a bracket constructed in accordance with my invention; Fig. 2 is a view of a bracket constructed in accordance with my invention, looking at the opposite side of the bracket; and Fig. 3 is a 40 detail perspective view of a form of locking means I employ to lock said bracket in position after being properly adjusted.

Referring now more particularly to the drawings, the numeral 1 represents a vertical 45 supporting bar, which is hinged to one face of a plate or block, 2, of preferably rectangular form, adapted to be screwed or otherwise securely fastened to the wall or a suitable object. The numeral 3 represents two parallel bars, which are pivotally connected near 50 their inner ends to the ends of said vertical supporting bar 1, and are connected at their outer or opposite ends by a connecting link or bar, 4. To retain said parallel bars 2 at 55 the proper adjustment, I employ a diagonal brace bar, 5, which is pivoted at or near its

inner end near the inner end of the lower parallel bar, as at 6, and is adapted to be locked at its opposite or outer end to the upper parallel bar by a locking device comprising a sliding clip, 7, slidably engaging and extending somewhat over the upper edge of the bar, and a cam lever, 8, eccentrically pivoted to said sliding clip as at 9, and also eccentrically pivoted to the outer end of said 65 diagonal brace bar, 5. The numeral 10 represents lazy-tongs, which are hingedly connected at their inner ends to said connecting link or bar, 4, and have hingedly connected to their outer ends a horizontal supporting 70 member, 12, comprising a horizontal arm, 13, and an oblique brace arm, 14, arranged below said horizontal arm and serving to brace the same.

It will be seen that by adjusting said parallel bars 3 at a suitable angle with respect to a vertical plane, said horizontal supporting member 12 may be raised or lowered to suit all requirements. It will also be seen that by employing lazy-tongs between said connecting link or bar 4 and said horizontal supporting member 12, said supporting member may be extended at a greater or less distance from the wall or the object to which my improved bracket is secured. Either or both 80 of said lazy-tongs and horizontal supporting member, 10 and 12, respectively, may be swung in a horizontal plane to secure the desired relative position of the tool or other object carried by said supporting member. 90

A particular feature of my invention resides in my improved means for automatically locking said parallel bars in position after they have been properly adjusted, as the greater the strain or weight exerted on or 95 carried by said horizontal supporting member, the greater the force with which said sliding clip, and the cam of said cam lever, clamp opposite sides of the upper parallel bar, thus obviating all liability of the bracket 100 slipping from position after being properly adjusted. To adjust said parallel bars at a suitable angle with respect to a vertical plane, and thereby raise or lower said horizontal supporting member, as the case may 105 be, it is only necessary to raise the free end of said cam lever to release the cam thereof and said sliding clip from engagement with the opposite edges of the upper parallel bar.

Having described my invention, I claim:

1. In a bracket, the combination, of two parallel bars, a brace bar pivoted to the

- lower bar, a sliding clip on the upper bar, a lever eccentrically pivoted to said brace bar, and having a cam at its pivoted end eccentrically pivoted to said clip, lazy-tongs hinged to adjacent ends of said parallel bars and arranged horizontally, and a horizontal supporting member hinged to the free end of said lazy-tongs, substantially as described.
2. In a bracket, the combination, of two parallel bars, a brace bar pivoted to the lower bar, a sliding clip on the upper bar, a lever eccentrically pivoted to said brace bar and having a cam at its pivoted end eccentrically pivoted to said clip, and lazy-tongs hinged to adjacent ends of said parallel bars and arranged horizontally.
3. In a bracket, the combination, of a supporting plate, two parallel bars hinged to said plate and adapted to swing in a horizontal plane, a diagonal brace bar pivoted to the lower parallel bar, a sliding clip on said upper parallel bar, a lever eccentrically pivoted to said brace bar and having a cam at its pivoted end eccentrically pivoted to said sliding clip.

4. In a bracket, the combination, of a supporting plate, two parallel bars hinged to said plate and adapted to swing in a horizontal plane, a diagonal brace bar pivoted to the lower parallel bar, a sliding clip on said upper parallel bar, a lever eccentrically pivoted to said brace bar and having a cam at its pivoted end eccentrically pivoted to said sliding clip, lazy-tongs hinged to the free ends of said parallel bars and a horizontal support hinged to the outer end of said lazy-tongs.

5. In a bracket, the combination, of two parallel bars, a diagonal brace bar pivoted to the lower parallel bar, a clip on said upper parallel bar, and a cam lever eccentrically pivoted to said clip and brace bar and adapted to co-act therewith in locking said parallel bars in an adjusted position.

In testimony whereof I have hereunto set my hand in presence of two subscribing witnesses.

LYMAN J. RHOADES.
